UNITED STATES PATENT OFFICE.

HENRY H. MERCER, OF CLAREMONT, NEW HAMPSHIRE, ASSIGNOR TO SULLIVAN MACHINERY COMPANY, A CORPORATION OF MASSACHUSETTS.

CHANNELING MECHANISM.

Application filed June 1, 1921. Serial No. 474,241.

Priority claimed from application filed June 1, 1921.

To all whom it may concern:

Be it known that I, HENRY H. MERCER, a citizen of the United States, residing at Claremont, in the county of Sullivan and State of New Hampshire, have invented certain new and useful Improvements in Channeling Mechanism, of which the following is a full, clear, and exact specification.

My invention relates to channeling mechanism.

It has for an object the provision of an improved channeling mechanism, and more specifically an improved channeling mechanism and method adapted to the cutting of relatively narrow, deep pits such as are used for supporting the toes of dams or similar structures.

In the accompanying drawing, I have shown for purposes of illustration, one form which my invention may assume in practice.

The figure is an end elevation of an illustrative embodiment of my improved channeling mechanism in operation in accordance with my improved system.

It has been found that, in digging suitable ditches to bed rock for receiving the concrete toes for dams, if a method consisting of alternate drilling and blasting is followed, the rock formation is considerably shattered at points adjacent the edges of the ditch and accordingly the security of the finished foundation is much less than would be the case were the rock to be removed without shattering the remaining portions.

As a general principle, however, it has been found that the necessary of these cuts is so slight as to render the use of an ordinary channeler in its normal manner wholly impracticable. It is for the purpose of permitting the use of a channeling machine for this and similar purposes that I have devised the improved apparatus and method of using the same described in this application.

In applying my improved method, an initial cut is first made at a slight angle to the vertical on each side of the desired groove, the cutting mechanism being arranged so that the cut formed will be wider at the bottom than at the top. The material is next removed to the bottom of the channel so cut, and a channeling machine lowered into the cut so formed, and arranged to run on tracks herein designated 1 which are mounted at a slight angle to the vertical and held

in position so that the weight of the channeler cannot tilt them further by extensible braces 2 extending between the opposite wall of the ditch or pit and the rails. For use on these rails, I provide a channeler mechanism which is in the main of ordinary construction, designated 3, which may be either of the electric or of the expansible fluid type and to which power may be conducted in any suitable manner. This channeler comprises a main frame 4 which is provided with wheels 5 having flanges 6 of greater width and strength than usual, and these are adapted to support a suitable portion of the weight of the channeler. For the purpose, however, of providing additional support, suitable hangers 7 are secured to the upper side of the channeler frame and mounted in these hangers are wheels 8 which rotate about an axis substantially perpendicular to the plane of the track and whose peripheries contact with the upper sides or lateral surfaces of the upper rails 1, whereby the channeler frame is, so to speak, hung on these rails. Further, to prevent any possibility of the weight of the channeler causing it to tilt by reason of a possible displacement of its center of gravity to a point whose vertical projection would not fall between the rails, additional hangers 9 provided with rollers 10 engaging the under side of the upper rail top are also secured to the frame 4. The standard 11 of the channeler, which is pivoted upon a bar 12 extending longitudinally of the frame 4, is at this time, it will be understood, tilted down to a position making a relatively small angle with the frame 4, and the channeler is then caused to run back and forth along the tracks while the channeler steels 13 are caused to impact upon the rock in their usual manner. When so supported, the channeler is arranged to put down a cut as close to one of the lateral walls of the pit in which it is moving as is possible without causing the channeler mechanism to foul, this cut also making a slight angle with the vertical. After the cut has been made to the requisite depth on one side, the machine is removed from the pit, the track changed, and the machine having been reversed, a cut on the opposite side of the cutting is made. Thereafter, upon the removal of the machine and the track, the material between the two cuts is drilled and blasted, and the separation of this material

from the main mass by the cuts prevents the shattering of the rock surrounding the pit that is being dug.

While I have in this application specifically described one embodiment which my invention may assume in practice, it will be understood that this form is shown for purposes of illustration, and that the same may be embodied in various other forms without departing from its spirit or the scope of the appended claims.

What I claim as new and desire to secure by Letters Patent is:

1. Channeling mechanism comprising a track tilted at an angle to the horizontal and a channeler adapted to normally run upon a horizontal track to cut a substantially vertical kerf, said channeler also being adapted to run on said tilted track and have the steels thereof operating at a slight angle to the vertical, whereby the distance between the cut so made and the projection of the upper side of the tilted track on a horizontal plane may be less than the width of the track.

2. Channeling mechanism comprising a track tilted at an angle to the horizontal and a channeler adapted to normally run upon a horizontal track to cut a substantially vertical kerf, said channeler also being adapted to run on said tilted track and have the steels thereof operating at a slight angle to the vertical, whereby the distance between the cut so made and the projection of the laterally most distant portion of said channeling mechanism may be less than the width of the track.

3. Channeling mechanism comprising a track tilted laterally at an angle to the horizontal, a channeler running on said track and comprising a truck and channeling devices tiltable about an axis on said truck, said channeling devices being disposable with the upper end thereof in a position wherein its projection on a horizontal plane will fall nearer the channel cut than the width of said track.

4. Channeling mechanism for working in a narrow cut comprising a track tilted laterally at an angle to the horizontal and supported at its upper and lower rails respectively by a side and the bottom of the cut, a channeler running on the track, and means for suspending the channeler from said upper rail.

5. Channeling mechanism for working in a narrow cut comprising a track tilted laterally at an angle to the horizontal and supported adjacent its upper and lower rails respectively by a side and the bottom of the cut, a channeler having wheels running on the track and rotating about axes parallel

to the plane of the latter, and means for preventing the channeler tilting about the lower rail.

6. Channeler mechanism for working in a narrow cut comprising a track tilted laterally at an angle to the horizontal and supported at its upper and lower rails respectively by a side and the bottom of the cut, a channeler running on the track, and means for holding said track in inclined position including bracing means extending between the same and a boundary of the cut.

7. Channeler mechanism for working in a narrow cut comprising a track tilted laterally at an angle to the horizontal and supported at its upper and lower rails respectively by a side and the bottom of the cut, a channeler running on the track, and means for bracing said track extending therebetween and the other wall of the cut.

8. Channeler mechanism for working in a narrow cut comprising a track tilted laterally at an angle to the horizontal and supported at its upper and lower rails respectively by a side and the bottom of the cut, means for bracing said track extending therebetween and the other wall of the cut, a channeler running on the track, and means for suspending the channeler from said upper rail.

9. Channeler mechanism for working in a narrow cut comprising a track tilted laterally at an angle to the horizontal and supported at its upper and lower rails respectively by a side and the bottom of the cut, means for bracing said track extending between each of the rails thereof and the other wall of the cut, a channeler running on the track, and means for suspending the channeler from said upper rail.

10. The method of channeling comprising mounting a channeler track upon one rail thereof upon the bottom of a cut and supporting the other rail against a side wall of the cut, and supporting a channeler on said rails with the steels thereof making a greater angle with the bottom of said cut than is made by said track.

11. Channeling mechanism comprising, in combination, a channeler supporting track disposed in inclined position with one rail thereof adjacent the bottom of a cut and the other rail thereof adjacent a side wall of the cut and spaced from the bottom thereof, and a channeler on said rails provided with cutting mechanism whose plane of movement makes a greater angle with the bottom of said cut than is made by said track.

In testimony whereof I affix my signature.

HENRY H. MERCER.
